UNITED STATES PATENT OFFICE.

SAMUEL R. PORT, OF MARTINSVILLE, INDIANA.

RECEPTACLE-COVER.

1,090,565.

Specification of Letters Patent. Patented Mar. 17, 1914.

Application filed July 12, 1913. Serial No. 778,705.

To all whom it may concern:

Be it known that I, SAMUEL R. PORT, a citizen of the United States, residing at Martinsville, in the county of Morgan and State 5 of Indiana, have invented a new and useful Receptacle-Cover, of which the following is a specification.

This invention relates to improvements in receptacle covers and more particularly to a 10 cover for ice cream tubs and similar vessels which contain ice or other cooling menstruum therein.

An object of the present invention is to provide a flexible receptacle cover permanently secured to the receptacle and with a 15 rope or cable secured to the said cover adapted to draw the same in close contact with the side walls of the receptacle to thereby prevent any cold air from escaping from the 20 receptacle and at the same time preventing the ingress of warm air.

A further object is to provide a flexible cover permanently secured to a receptacle and composed of material having a high 25 thermal resistance to thereby prevent excessive heat losses due to convection and radiation.

A further object is to provide an outer 30 layer of canvas with an outer depending rim doubled upon itself and to the lower edge of which is loosely secured a tying rope whereby the edge of the rim may be drawn tightly against the side walls of the receptacle to form an air tight juncture therewith and to 35 secure to the canvas a layer of pitch or tar paper substantially air and water proof and to protect the said paper lining by a coating of burlap.

With the foregoing and other objects in 40 view which will appear as the description proceeds, the invention resides in the combination and arrangement of parts and in the details of construction hereinafter described and claimed, it being understood 45 that changes in the precise embodiment of the invention herein disclosed, can be made within the scope of what is claimed, without departing from the spirit of the invention.

In the drawings accompanying this specification and forming a part thereof, the preferable form of my invention is illustrated, in which:

Figure 1 is a sectional view taken along

the longitudinal axis of a receptacle with my improved cover positioned thereon. Fig. 55 2 is a side view in elevation of the receptacle with the cover thrown back. Fig. 3 is a view in perspective of the receptacle with my improved cover secured thereto and with a portion broken away to more clearly disclose the structural details of the latter. Fig. 4 is a view in perspective of the cover.

Referring to the drawings in which similar reference numerals designate corresponding parts throughout the several views, 65 1 is an ice cream containing receptacle and as is the general construction of this class of articles, it is frusto-conical in general outline, the top base being the larger. The receptacle 1 is provided with the handle 2, 70 the same being mentioned due to its coaction with the various other elements and provides additional means whereby the flexible cover hereinafter described is held in place. The flexible cover is provided with 75 the top 3 circular in outline and conforming to the top of the receptacle 1. The top 3 includes the outer layer 4 preferably formed of canvas to the inner surface of which is secured the lining 5 preferably formed of 80 tar or pitch paper and which thereby renders the entire cover water and air proof and also prevents any large amount of heat convection from taking place. As a further means for preventing the convection of heat 85 through the cover and also to protect the tar or pitch paper lining 5, the burlap 6 is provided and is rigidly and permanently secured to the said paper lining.

The outer layer of canvas 4 is bent downwardly to form the depending rim 7, the canvas being bent upon itself at the lower extremity thereof as at 8 so that the rim 7 will be of double thickness throughout. The extreme end 9 of the canvas is rigidly sewed 95 or otherwise held to the burlap 6. From the foregoing it will be apparent that the cover is of three thicknesses at the top and of two thicknesses of canvas throughout the rim, the same being amply sufficient to prevent 100 the ingress of hot air and the escape of cold air from the receptacle when the cover is secured in position thereon. However, the exact number of the layers of lining and burlap may be varied, according to the use 105 and abuse the cover is designed to withstand.

The rim 7 of the flexible cover is provided with two eyelets or gromets through which extend the holding or securing screws 11 the same being embedded in the side walls 5 of the receptacle to permanently secure the flexible cover thereto at one portion thereof. By "permanently" it is meant that the cover is intended to remain secured to the side walls of the receptacle during the use- 10 ful life thereof and not to be entirely removed after each trip of the receptacle as is now the practice. The eyelets 10 extend entirely through both layers of the rim of the cover so that the screws 11 can pass 15 therethrough for the engaging of the side walls of the receptacle. Positioned in substantial diametric opposition to the eyelets 10 are the eyelets 12, two in number, and which extend through only the outer layer 20 of the canvas rim so that they communicate with the space between the layers of the said rim. Extending entirely around the cover and disposed between the layers of the rim 7 is a tying rope or cable 13, the ends 25 of which pass through the eyelets 12 and are designed to be knotted or tied together to thereby draw the rim tightly against the side walls of the receptacle 1. The free ends 15 of the rope or cable are then passed 30 downwardly and engage the handle 2 for the retaining of what is termed the front portion of the cover upon the receptacle. The rope or cable 13 is disposed adjacent the lower extremity of the rim 7 and may 35 be held in such relation by a sewing of the layers of the rim or other suitable means. However, it is to be noted that the rope 13 is slidably disposed between the said layers so that the only stress exerted upon the 40 layers of the canvas will be to hold the same tightly against the side walls of the receptacle.

The advantages of a cover such as I have above described will be readily apparent 45 and my cover embodies all those advantages of a flexible cover over a rigid one. The particular flexible cover herein described embodies certain particular advantages, among which the following are men- 50 tioned:—The cover is permanently secured to the receptacle and may be flexed back from above the receptacle opening about the securing means. The said securing means prevents the cover from contacting with the 55 ground and the accompanying unsanitary result. The outer layer of the cover being formed of canvas is especially adapted to withstand hard usage and the long life of the article is thereby insured. The receptacle 1 being of substantially frusto-conical outline and the securing of the rope at some distance from the upper edge thereof prevents the cover from riding off the recepta-

cle, additional securing means being provided by the securing of the tying rope 65 about the handle 2. The air-tight manner in which the rim is secured to and held against the side walls of the receptacle prevents any outward circulation of cold air and the inward circulation of warm air and the simplicity of construction renders the device susceptible of cheap manufacture, as will be appreciated.

What I claim is:—

1. A receptacle cover comprising a top, 75 said top including an outer body member, a member secured thereto and having a high thermal resistance, a lining secured to said body member and protecting said heat resisting member, the body portion of said top bent downward at its outer edge, looped 80 upon itself and forming a rim including a plurality of layers, said rim provided with a reinforced opening extending entirely therethrough, said rim further provided 85 with two reinforced openings extending through the outer layer of the rim, and a tying rope slidably disposed between the rim layers and extending through the said last mentioned openings. 90

2. A receptacle cover comprising a top, 95 said top including an outer body member, a member secured thereto and having a high thermal resistance, a lining secured to said body member and protecting said heat resisting member, the body portion of said top bent downward at its outer edge, looped 100 upon itself and forming a rim including a plurality of layers, said rim provided with a reinforced opening extending entirely therethrough, said rim further provided with two reinforced openings extending through the outer layer of the rim, a tying rope slidably disposed between the rim layers and extending through the said last mentioned openings, and means extending 105 between the layers of the rim confining the said tying rope to the lower extremity thereof.

3. A cover for a frusto-conical receptacle 110 comprising a top, a lining secured thereto, a member interposed between the lining and the top and having a high thermal resistance, the outer edge of said top bent downward and looped upon itself at its lower 115 edge to form a rim including a plurality of layers, said rim provided with a reinforced opening extending therethrough, means extending through said opening securing the same to the said receptacle, said 120 rim provided at diametrically opposed portions with two reinforced openings extending through the outer layer of said rim, a tying rope extending through the last mentioned openings and slidably disposed between the rim layers, means for 125

confining the said tying rope to the lower extremity of said rim, said receptacle provided with an outstanding member, said tying rope engaging said outstanding member and holding the receptacle cover in position.

In testimony that I claim the foregoing as

my own, I have hereto affixed my signature in the presence of two witnesses.
